United States Patent Office.

JACOB EBERHARDT, OF NEWARK, NEW JERSEY.

Letters Patent No. 79,059, dated June 23, 1868.

IMPROVEMENT IN HAT-BLOCKING MACHINES.

The Schedule referred to in these Letters Patent and making part of the same.

TO ALL WHOM IT MAY CONCERN:

Be it known that I, JACOB EBERHARDT, of Newark, in the county of Essex, and State of New Jersey, have invented a new and improved Hat-Blocking Machine; and I do hereby declare that the following is a full, clear, and exact description thereof, which will enable others skilled in the art to make and use the same, reference being had to the accompanying drawings, forming part of this specification.

The drawing represents a sectional elevation of my improved hat-blocking machine.

This invention relates to a device for preserving the shape of the brim of a hat while the body is being formed between a metallic and an elastic die; and it consists in placing an annular elastic plate around the elastic male die, and resting upon the frame of the latter, and in placing over said elastic plate an annular metallic plate, whereby, as the female die is forced down, to form the hat-body, the rim of the latter will be pressed upon a yielding surface, and therefore prevented from being pressed out of shape, and destroyed, as would be the case if clamped between rigid and unyielding surfaces.

A, in the drawing, represents a rubber or other elastic cone, of suitable form, fitted upon a suitable stationary or reciprocating frame, B, as shown.

C is a cast-iron or other metal die, with an indentation of such form as is to be imparted to the hat.

The hat-body is fitted around and upon the cone, and the same is then forced into the die, or the latter is forced towards and over the die, and the cone will thereby be compressed so as to fit well into the die, and the hat-body on it will thus also receive the shape of the die.

The brim of the hat is formed between the lower face of the die and a ring, D, which rests upon an elastic ring, E, that is supported by the frame B.

By this construction it will be perceived that, as the dies are brought together, the brim is held upon a yielding surface, and cannot be pressed out of shape.

I claim as new, and desire to secure by Letters Patent—

The brim-preserved, consisting of the elastic annular plate E, between the metallic annular plate D, and frame B, in combination with the elastic male die A and metallic female die C, as herein described, for the purpose specified.
